UNITED STATES PATENT OFFICE.

ROBERT J. MITCHELL, OF GIRARD, ILLINOIS.

THILL-COUPING.

SPECIFICATION forming part of Letters Patent No. 253,411, dated February 7, 1882.

Application filed November 29, 1881. (No model.)

To all whom it may concern:

Be it known that I, ROBERT J. MITCHELL, of Girard, Macoupin county, Illinois, have invented a new and useful Improvement in Thill-
5 Couplings, of which the following is a full, clear and exact description.

Reference is to be had to the accompanying drawings, forming part of this specification, in which similar letters of reference indicate corresponding parts in all the figures.

Figure 1 is a sectional side elevation of my improvement. Fig. 2 is a plan view of the same. Fig. 3 is a front elevation of the same, the thill-iron being removed, and Fig. 4 is a perspective view of the elastic packing.

The object of this invention is to prevent the rattling of ordinary thill-couplings.

A represents the bow, B the yoke, C the lugs, D the thill-iron, and E the coupling-bolt, 20 of an ordinary thill-coupling.

F is a block made of rubber or other elastic material in triangular form, and with its face concaved to fit upon the eye of the thill-iron D. The rear side of the elastic block or packing F 25 has a groove, G, formed in it to receive the T-bolt H. The ends of the cross-head of the bolt H rest against the lower edges of the lugs C, as shown in Fig. 3. The bolt H passes perpendicularly upward through the groove in the elastic packing F and through a hole in the middle part of a metal plate, I, which rests upon the top of the elastic packing F. Upon

the upper end of the bolt H is screwed a nut, J. With this construction, when the nut J is screwed down the elastic packing F is pressed downward and slightly forward, so as to hold the thill-iron D firmly in place and entirely prevent rattling. With this construction, also, the pressure against the thill-iron can be increased and lessened by screwing the nut J down and up.

K is a plate, of leather or other suitable material, interposed between the rubber packing F and the thill-iron D to take the wear, and which has its lower end notched to receive the bolt H. The leather plate K is made thin at its upper end and thicker at its lower end, and is made of such a length that its lower end will rest upon the cross-head of the T-bolt, so that the said leather plate cannot work out.

Having thus described my invention, I claim as new and desire to secure by Letters Patent—

The combination, with the bow A, lugs C, thill-iron D, the clamping device H J, and the packing strip of leather, K, of the angular concaved block G, made of compressible material and provided with the rear slot, G, said block being removable or adjustable by simply loosening the clamp, as described.

ROBERT J. MITCHELL.
